UNITED STATES PATENT OFFICE

148,820

DESIGN FOR A TRAILER

Gerhard R. Schutes, Saginaw, Mich., assignor to Spartan Aircraft Company, Tulsa, Okla.

Application November 20, 1946, Serial No. 134,958

Term of patent 14 years

(Cl. D14—3)

To all whom it may concern:

Be it known that I, Gerhard R. Schutes, a citizen of the United States, residing at Saginaw, in the county of Saginaw and State of Michigan, have invented a new, original, and ornamental Design for Trailers, of which the following is a specification, reference being had to the accompanying drawings, forming part thereof.

In the drawings:

Fig. 1 is a side elevational view of a trailer showing my new design.

Fig. 2 is a similar view from the opposite side of the trailer.

Fig. 3 is a front elevational view.

Fig. 4 is a rear elevational view.

The present application is a continuation-in-part of my application, Serial No. D. 123,861, now abandoned.

The characteristic features of my design reside in the portions shown by full lines in the drawings.

I claim:

The ornamental design for a trailer, as shown and described.

GERHARD R. SCHUTES.
